UNITED STATES PATENT OFFICE.

CHARLES W. KIRSCH AND HENRY J. LAHMEYER, OF STURGIS, MICHIGAN.

PANEL-CURTAIN FRAME.

1,240,581.

Specification of Letters Patent. Patented Sept. 18, 1917.

Application filed March 8, 1916. Serial No. 82,862.

To all whom it may concern:

Be it known that we, CHARLES W. KIRSCH, of Sturgis, St. Joseph county, Michigan, and HENRY J. LAHMEYER, of Sturgis, St. Joseph county, Michigan, both citizens of the United States, have invented certain new and useful Improvements in Panel-Curtain Frames; and we do hereby declare the following to be a full, clear, and exact description of the invention, such as will enable others skilled in the art to which it appertains to make and use the same.

This invention relates to improvements in curtain fixtures, and more particularly to frames adapted to receive panel-curtains to be disposed behind the glass panes in doors and windows, the object being to provide a simple and efficient device of this character which affords a relatively rigid frame which 20 may be readily hinged or rigidly secured to the door, window-frame or window-sash.

The invention consists in the features of construction and combinations of parts hereinafter fully described and particularly 25 claimed.

In the accompanying drawings illustrating a suitable embodiment of the invention:

Figure —1— is a view in elevation of a curtain frame constructed in accordance 30 with the invention.

Fig. —2— is a horizontal section on an enlarged scale on the line 2—2 of Fig. —1—.

Fig. —3— is a fragmentary detail horizontal section on the line 3—3 of Fig. —4—.

Fig. —4— is a fragmentary detail view 35 in elevation of one of the corners of the frame.

Fig. —5— is a view similar to Fig. —1— showing the curtain-frame mounted in a 40 window-frame, and equipped with shade-roller hangers and shade-roller.

Fig. —6— is a fragmentary detail horizontal section on the line 6—6 of Fig. —5—.

Fig. —7— is a detail vertical section on the 45 line 7—7 of Fig. —6—.

Fig. —8— is a fragmentary detail horizontal section on the line 8—8 of Fig. —7—.

Fig. —9— is a view in elevation of a panel curtain frame embodying the invention 50 equipped with cross-bars in imitation of lattice-work.

Fig. —10— is a fragmentary detail view in elevation showing the panel frame having a brace secured therein.

55 The main object of the present invention

is to provide a knock-down panel-frame for curtains in which certain of the connecting members constitute hinge members by means of which the frame is secured to the door, window-sash, window-frame, or the like, so 60 that the frame carrying the curtain may be swung away from the glass for purposes of giving access to the latter for cleaning the same without requiring the disassembling of the frame and removal of the curtains for 65 this purpose.

A further object of the invention is to provide a knock-down frame which is very easily and quickly assembled, and easily and quickly mounted and demounted, and which 70 when assembled provides the requisite rigidity for maintaining a panel curtain properly taut to present a smooth surface in front of the glass of the door or window.

Another object of the invention is to provide a panel curtain-frame which is also adapted to receive shade-roller hangers for supporting a shade roller in front of the window-pane, and which is adapted to be swung away with the frame for access to the 80 glass to clean the same.

Other objects of the invention will appear from the following specification.

Referring now to the drawings, it will be seen that the panel-curtain frame comprises 85 corner members 1 each having two transversely disposed arms 2 each of which is C-shaped in cross-section, and adapted to telescopically receive similarly shaped rods 3 extending at angles to each other, and connecting the several corner members of the rectangular frame with each other. The outer side flange 4 of one of the arms 2 of each of said corner members extends from the outer end of said arm to the farthest removed corner of said member, the similar flange 5 of the other arm 2 being shorter to provide an open space at said corner to receive the flange 6 of a hinge member. The latter is, as shown in Fig. —3—, integral 90 with the body of the corner member, and consists of a tongue extending outwardly from the middle portion of the arm equipped with the flange 4, the flange 6 being folded over upon the body of the middle portion, and 95 being preferably spot-welded to the latter. A sleeve is thus formed to receive the pivot pin 7 by means of which said hinge member is pivotally secured to a companion hinge bracket 8 adapted to be secured to the door, 100

window-sash or window-frame, as shown. The hinge member 8 consists preferably of an L-shaped member, one flange of which is provided with perforations for the passage 5 of the screws 9 for securing the same to the door, or the like, and the other flange of which has a bifurcated outer end portion, the tongues forming which are bent over to provide sleeves 10 between which the sleeves of 10 the hinge members 6 are received and through which the pivot pin 7 is adapted to pass.

As shown in Fig. —1— each of the four corner members is adapted to be hinged to 15 the door, or other support, the pivot pins 7 being removable, so that when the same are removed from the hinges at one side of the frame, the latter may be swung on the remaining hinges. The frame is thus adapted 20 to be swung in either direction, as desired, and by removing all of the pivot pins 7, may be entirely removed from the door or window without removing the curtain or knocking down the frame.

25 Where the frame is of unusual length the rod members 3 connecting the vertical corner members are equipped with telescopic sleeves 11 of the same cross-section as the arms 2 of the corner members, and upon the 30 rod members 3 between their ends. Said members 11 are also preferably equipped with hinge members 12 integral therewith adapted to be pivoted to hinge members 8 by means of pivot pins 7 in the same manner as 35 the aforesaid corner members 1.

After assembling the frame as shown in Fig. —1—, the various parts are locked against relative movement by means of the curtain rod locks 13 fully described and 40 claimed in Letters Patent No. 1,142,438, granted to me on the 8th day of June, 1915, said locks each comprising an elliptical disk provided with a longitudinal slot in which a suitable spanner wrench is adapted to be received for turning said disks to present their longer diameters transversely to and thereby expanding the flanges of the inner telescopic members 3 to firmly frictionally engage the flanges of the receiving member, as more 45 particularly shown in Fig. —4—.

50 In some instances it is desirable to employ window shades interposed between the panel curtains and the window pane, and it is desirable also to avoid mounting such fixtures on the woodwork contiguous to the window-panes for obvious reasons. Hence, to overcome this objection the window-shade brackets 14 may be mounted on the frame, each of 55 said brackets being provided with a flange 60 15, spot-welded or otherwise suitably secured to a C-shaped base 16 adapted to fit telescopically within the rod members 3, as shown in Figs. —7— and —8—. The said flanges 16 are preferably disposed within 65 those portions of the rod members 3 pro-

jecting into the vertical arms of the upper corner members 1 of the frame, and are frictionally engaged within said members by means of the locking disks 17 corresponding to the disks 13, shown in Fig. —4—. 70 Said shade roller brackets are thus rigidly held in place as will be obvious, and are adapted to receive window shades and rollers 18, as shown.

In making up these frames it is preferable 75 to cut the rod members 3 to proper lengths from a long length thereof, but it will be obvious that such frames may be rendered adjustable by projecting the rod members 3 more or less distance into the arms of the 80 corner members 1, and such rod members may be made in shorter sections and coupled by means of the sleeves 11 by projecting the ends of said rod members 3 a greater or less distance into the same. Illustration hereof 85 is believed to be superfluous as the same is fully disclosed in my copending application for Letters Patent for curtain rod filed February 14, 1916, Ser. No. 78190.

The embodiments illustrated in the drawings and hereinbefore described are 90 obviously capable of modification and variation without departing from the invention as defined in the appended claim.

The construction may be further modified 95 to produce lattice-work, panel curtain frames, or merely lattice-work frames to be mounted in front of windows to give the effect of a plurality of small panes where a large one is employed by interposing between the top, bottom and side frame members the cross-rods 19 and 20 respectively, utilizing for the purpose T-shaped and X-shaped fixtures 21 and 22 respectively, in which the rods 19 and 20, and the top and 100 bottom and side members of the frame respectively, are adapted to be similarly engaged and secured. In this manner any desired design of panel curtain frame may be produced, it being obvious that the angular 105 members 23, shown in Fig. —10—, may be employed in connection with the other frame members illustrated in the remaining figures to produce frames of any desired design, said members 23 being adapted to be secured 110 by means of the fixtures 24, having angularly disposed arms 25 receiving said angular rod 23 for attaching the same to the vertically and horizontally disposed frame-members.

115 120 We claim as our invention:

A knock-down curtain frame comprising L-shaped channeled corner members having overhanging side flanges, rod members of similar cross-section adapted to be telescopically received and engaged in said corner members to provide a rectangular frame adapted to receive a panel curtain or the like, and means within the engaging ends of the rods for expanding same to provide a 130

substantially rigid engagement between same and the opposed flanges of the corner members, whereby said frame can be readily adjusted to desired dimensions and the parts quickly secured in such position in condition to be readily taken apart.

In testimony whereof we have signed our

names in presence of two subscribing witnesses.
